UNITED STATES PATENT OFFICE.

WILLIAM HARTLEY, OF LEICESTER, ENGLAND, ASSIGNOR OF ONE-HALF TO THOMAS FIELDING JOHNSON, OF LEICESTER, ENGLAND.

SPINNING-MACHINE.

1,113,434.

Specification of Letters Patent.

Patented Oct. 13, 1914.

Application filed March 27, 1914. Serial No. 827,527.

To all whom it may concern:

Be it known that I, WILLIAM HARTLEY, a subject of the King of Great Britain, citizen of Leicester, England, residing at Bond 5 street, Leicester, in the county of Leicester, England, have invented new and useful Improvements in or Relating to Spinning-Machines, of which the following is a specification.

10 This invention relates to spinning machines and more especially to flier spinning frames, the object being to provide simple and efficient means for preventing displacement of the washers from the lifter plate 15 when the bobbins are doffed. The said means may, and preferably do also serve to separate the bobbins from the washers prior to the removal of the bobbins or the lowering of the lifter plate from bobbins. As is 20 known, when the bobbins are raised from the lifter plate or the latter is lowered from the bobbins during the operation of doffing, there is a tendency for the washers—carried by the lifter plate and through which the 25 spindles also pass—to cling or stick to the end of the bobbin with the result that said washers are sometimes accidentally removed with the bobbins or are displaced thereby necessitating expenditure of time to locate 30 them on the lifter plate again. To prevent this, the present invention provides means which are adapted to be brought into engagement or contact with the washers prior to the bobbins being doffed, said means serving 35 to hold the washers in place on the lifter plate when the bobbins are raised therefrom or during the operation of doffing when the lifter plate is lowered from the bobbins and spindles as in a machine where the bobbins 40 are removed from the bottom ends of the spindles.

In its simplest form, the invention comprises a series of devices arranged to be brought into interposition between the bobbins and washers to hold the latter on the lifter plate. These interposing devices are preferably specially shaped or formed to also effect separation of the bobbins from the washers. The said devices may be actuated individually or in unison but by preference they are all moved together.

In further describing the invention, reference will be made to the accompanying drawing which illustrates a practical embodiment of the invention and shows same 55 applied to the spindles of a flier spinning machine of the type wherein the bobbins are doffed downward from the bottom ends of the spindles.

In the drawing referred to:—Figure 1 is 60 a perspective view of part of a lifter plate the washer holding devices being shown in the normal or inoperative position. Fig. 2 is a similar view to Fig. 1 and shows the washer holding devices in operation. Figs. 65 3 and 4 are partly sectional elevations showing the lifter plate and washer holding devices according to Figs. 1 and 2 in use with the spindles and bobbins. Fig. 5 is a cross section of the lifter plate. Fig. 6 is a plan 70 of same hereinafter referred to. Figs. 7 and 8 are similar views to Figs. 1 and 2 and show a slightly modified form of the washer holding means. Fig. 9 illustrates a detailed feature hereinafter described. 75

Like parts are designated by the same reference characters in all the figures of the drawing.

According to the concrete example of the invention shown in the drawing, (Figs. 1 80 to 6), a number of plates 1 (one for each washer *a*) disposed transversely on the lifter plate *b* are secured at each end to a bar 2 slidably supported by bearings 3 on the lifter plate *b* and capable of longitudinal 85 movement parallel to the lifter plate. At one or each end of the lifter plate the slide bars 2 are connected by a cross bar 4 to which is attached a handle 5 by which the longitudinal movement of said bars 2 may 90 be effected.

The upper side of the lifter plate *b* is, in the vicinity of each spindle *c*, recessed as shown at 6 for the reception of the washers *a* so that the latter are sunk into the lifter 95 plate and made level with the upper side thereof. This is to enable the aforesaid transverse plates 1, when the slide bars 2 are moved in the direction indicated by the arrows in Fig. 1, to move over the upper 100 side of the washers *a* as shown in Figs. 2 and 4, in which position said plates 1 will

hold the washers down in the recesses 6 and prevent them rising with the bobbins when the latter are lifted, or sticking to the bobbins when the lifter plate is lowered from 5 the bobbins.

The lifter plate *b* need not be recessed if the transverse plates 1 are arranged to stand above the lifter plate the thickness of the washers *a*, but it is preferable that said 10 holder plates 1 should lie flat on the lifter plate in which case the washers require to be sunk as previously described.

Each holder plate 1 has a thin edge 7 so that when moved to the operative position 15 it will be able to force its way between the washer *a* and bobbin *d*. By forming the plates 1 with thickened centers and with a rounded upper surface as shown they will, when penetrating between the washers *a* and 20 bobbins *d*, raise the latter by the entrance of the thick part under the ends of the bobbin as shown in Fig. 4, thus effecting a separation of the bobbins and their washers prior to the doffing operation.

25 The bearings 3 (see Figs. 5 and 6) are conveniently of the block type and attached to the underside of the lifter plate *b* by screws 8.

Any suitable means such as pins and slots 30 may be made use of to limit the travel of the slide bars 2 and plates 1 in each direction.

In an alternative arrangement (Figs. 7 and 8) the slide bar 2 on each side of the 35 lifter plate *b* has independent holding plates 9 and is capable of movement in an opposite direction to the other to bring the holding plates into position over the washers on opposite sides of the spindles as shown in Fig.

40 8. In this construction each washer is held down at two diametrically opposite points, the slide bars 2 being movable independently, or they may as shown be coupled together and actuated simultaneously by a 45 member common to both (for example by a handle or lever 10) movable about a fulcrum 11 located intermediate of the two slide bars 2. In this construction each holder plate 9 is attached rigidly to its slide rod.

50 The holder plates may be shaped as shown at 12 in Fig. 9 to extend partly around the spindles so that when occupying the operative position they may be located well over the faces of the washers.

55 Claims.

1. In a spinning machine, in combination, 60 a bobbin lifter plate, washers carried thereby, and means adapted to be moved into engagement with the washers and serve to prevent displacement thereof during the operation of doffing the bobbins.

2. In a spinning machine, in combination, a bobbin lifter plate, washers carried thereby, and means adapted to separate the wash-

ers and bobbins prior to the doffing of the 65 latter and to prevent displacement of said washers during the doffing operation.

3. In a spinning machine, in combination, 70 a bobbin lifter plate, washers carried thereby by which the bobbins are supported, and a series of devices arranged to be brought into interposition between the bobbins and said washers to hold the latter upon the lifter plate when said plate and bobbins are separated for doffing the bobbins. 75

4. In a spinning machine, in combination, 80 a bobbin lifter plate, washers carried thereby by which the bobbins are supported, and a series of devices (one for each washer) arranged to be brought into interposition between the bobbins and said washers to hold the latter upon the lifter plate when said plate and bobbins are separated for doffing the bobbins, and means for effecting a simultaneous movement of said devices to and 85 from the operative position.

5. In a spinning machine having a bobbin lifter plate and washers carried thereby, the combination with the lifter plate of a series 90 of transverse plates (one for each washer) extending over the lifter plate, a slide bar supported by the lifter plate and to which said transverse plates are attached, said bar being movable longitudinally to bring the transverse plates into and out of position 95 over the washers, for the purpose described.

6. In a spinning machine having a bobbin lifter plate and washers carried thereby, the combination with the lifter plate of a series 100 of transverse plates (one for each washer) extending over the lifter plate, slide bars supported by and situated one on each side of the lifter plate and to which said transverse plates are attached to each end, said bars being movable longitudinally to bring 105 the transverse plates into and out of position over the washers, for the purpose described.

7. In a spinning machine having a bobbin lifter plate and washers carried thereby, the combination with the lifter plate of a series 110 of transverse plates (one for each washer) extending over the lifter plate slide bars situated one on each side of the lifter plate and to which said transverse plates are attached at each end, bearings on the lifter 115 plate supporting said slide bars, and means to couple said slide bars together rigidly so that when actuated they move longitudinally in company for the purpose described.

8. In a spinning machine having a bobbin 120 lifter plate and washers carried thereby, the combination with the lifter plate of washer holding means movable into and out of position over the washers, the latter being located in recesses in the lifter plate. 125

9. In a spinning machine having a bobbin lifter plate and washers carried thereby by which the bobbins are supported, washer

holding means consisting of a series of devices movable into interposition between the washers and bobbins and having a thin front edge and a thickened middle part whereby
5 the bobbins are raised from the washers when the said devices are moved to the operative position.

In testimony whereof I have signed my name to this specification in the presence of two subscribing witnesses.

WILLIAM HARTLEY.
